UNITED STATES PATENT OFFICE

HAROLD W. SHONNARD, OF MONTCLAIR, NEW JERSEY, ASSIGNOR TO ELEVATOR SUPPLIES COMPANY, INC., A CORPORATION OF NEW JERSEY

SAFETY DEVICE FOR ELEVATOR DOORS

Application filed March 17, 1925. Serial No. 16,214.

The present invention has relation to means for preventing injuries to passengers arising from accidental contact with the folding or collapsible doors customarily used on elevators in office buildings, depots, factories etc.; and, indeed, in any locality where sliding doors of the common "lazy-tongs" construction are used.

Collapsible doors of the "lazy-tongs" type are very extensively used in elevators and in other places where rigid economy of space is requisite; and, while doors and gates of this type present the advantage of a maximum of economy in space, they are nevertheless, a source of recognized danger, in that the folding bars of which they are constructed will catch and injure the clothing or fingers of any person who by carelessness or overcrowding is pressed against them.

20 This danger is especially emphasized in modern elevators, both because these conveyances are often crowded in the rush hours, and because these doors are often operated automatically by machinery, so that they are not under the complete control of the operators. In consequence injury to passengers often results from their use, and it is the object of the present invention to guard against this source of danger, and to prevent the 30 catching of the persons or clothing of passengers by doors or gates of the character mentioned.

For this purpose I provide a flexible mantle or curtain on the inside of the door or gate, together with automatic means for keeping the same always stretched in a position to prevent any object from being thrust in between the folding bars of which the door is made. Preferably this mantle or curtain is so proportioned as to cover only that portion of the vertical height of the door or gate against which there is danger of contact with the person or clothing of a passenger, leaving adequate space above or below, or both above and below the guard or curtain to prevent an unobstructed view from within outward or from without inward.

45 The invention is illustrated in a preferred form in the accompanying drawings, where in Figure 1 is a view in elevation of an eleva-

tor door of a well known type as seen from within, Figure 2 is a view on a larger scale, partly in section and partly in elevation of the preferred form of curtain roller and guard, Figure 3 is a plan view of the device shown in Figure 2, and Figure 4 is a horizontal sectional view of the same taken on the line 4—4 of Figure 2.

50 My invention covers the use of a single guard or curtain in combination with a folding door of the character already mentioned, but, as it may also be embodied in a structure comprising a plurality of such guards or curtains, I have illustrated the invention, by way of example, in Figure 1, as embodied in a 55 structure comprising two of such guards. It will, of course, be understood that, where it is found desirable to employ more than two such guards or curtains, the invention will be utilized by supplying as many of these as 60 may be necessary.

In Figure 1 a well known form of "lazy tongs" door or gate 9 is illustrated, composed of vertical bars 10, united by slidable, pivoted crossed bars 11 and extends entirely across 75 the opening in the cage as shown. These are supported by and move upon a framework 12 of dimensions suited to the particular purpose in hand. The opening and closing of this door may be accomplished by hand, utilizing the handle 13, or any automatic means 80 may be used for the purpose.

85 In order to prevent the danger of catching the clothing or hands or fingers of those located near the gate, by the movable bars, I provide one or more guards or curtains 14, which cover those portions of the gate which are likely to come into contact with the clothing or persons of passengers. This curtain may be made of any suitable fabric, or 90 of leather, flexible metal, or of any material or construction which will answer the purpose. Such a guard may, of course, cover the entire door, without departing from the invention, but I prefer to cover only such 95 parts of the door as are likely to be a source of danger, as shown in Figure 1. This makes it still possible for a person on either side of the door or gate to see what is going on upon the other side.

Means are provided whereby the guards or curtains 14 are kept continually stretched flat against the doors or gates whatever the position of the latter and for this purpose I prefer a self-contained unitary mounting exemplified by the structure shown in detail in Figures 2, 3 and 4.

The curtain 14 is secured to and rolls upon a roller 15, a part at least of which is hollow, so as to accommodate a spiral spring 16.

The plate 17 at one end of the roller is revolvably mounted upon a fixed pin 18, which has a non-circular portion 19 fitting removably into a similarly shaped socket 20 in the head 21. At the opposite end of the roller, a plate 22 is provided with a pin 23, turning in a bearing 24 in the head 25. The weight of the roller is preferably carried by the ball bearings 26. The head 21 is secured by screws 27 to the vertical support 28, to the opposite end of which is also secured the head 25, by the screws 29. The support 28 is secured in any desired manner to a suitable support, as for instance one of the vertical bars 10 of the door or gate, (see Figure 1).

The roller and the rolled portion of the curtain is preferably protected by a guard 30 of cylindrical shape, but not entirely encircling the roller, which guard is preferably made of thin sheet metal preferably reinforced by a stout curved bracket 31, secured to the support 28 by screws 32. This bracket 31 prevents the buckling or denting of the metal guard 30. This guard is preferably secured at its ends to the heads 21 and 25.

The structure so described will be seen to constitute, with the curtain 14, a unitary structure capable of ready application to any door or gate. This structure may be secured either to the gate as shown or to any convenient support near the gate.

One end of the spring 16 is fixed to the roller 15, as at 33 and the other to the non-rotatable pin 18 (see Figure 2) and this spring is so arranged as to be tightened or wound up when the curtain 14 is unrolled. The effort of the spring tends, therefore, at all times to roll the curtain upon the roller 15, so that as the door, to which the forward edge of the curtain is attached, is slid back and forth in closing and unclosing, the curtain 14 is always kept stretched flat against the door.

Where the width of the door is not too great it will be sufficient to supply one curtain of this kind with its forward edge secured to the door. Where, however, the full movement of the door is so great that a single curtain would tend to sag between its ends, two or more curtains may be used, as shown in Figure 1.

The embodiment of the invention illustrated in the drawings show two curtains arranged in tandem relation, each of which is

mounted entirely and solely within the elevator cage, and so arranged that the forward curtain winds and unwinds at one end thereof, said end being disposed within the casing 30 in Fig. 1 at approximately the center of the gate 9. The other end of the forward curtain 14 is shown as fixed to the free end—that is, the end where the handle 13 is located—of the gate 9. It will be noted further that this forward curtain 14 extends from adjacent the cage floor to another point substantially level with the handle 13 of the cage 9. The rear curtain 14 likewise extends from adjacent the cage floor to a similar height on the gate 9. The use of two curtains arranged in tandem as illustrated is, I believe, a novel feature of this invention, but it is of course not the only novel feature. Other novel features reside in the construction and method of mounting each curtain, and such construction and mounting means is employed in each installation irrespective of the number of curtains in the installation.

The use of a plurality of curtains in tandem improves the structure by making it possible to keep the curtains flat by the use of relatively weak springs and thereby prevents undue interference with the counterbalancing of the collapsible gate by the tension of the spring which winds up the curtain. Moreover, a relatively uniform tension is provided upon the curtain, inasmuch as the amount of deflection of the springs is divided between two springs, and hence the total deflection is approximately one-half of the total deflection which would be necessary in the case of a single spring. Moreover, compactness is attained inasmuch as the curtains roll upon two rollers; and hence the increase in diameter of each of the rolled curtains is approximately one-half of a corresponding length single curtain rolled on a single roll. This feature is furthermore of importance in a construction where the winding spring is contained within the roller, as the lighter spring and lesser diameter of rolled curtain both contribute to the compactness of the device.

Where this arrangement is found necessary, I prefer to connect the respective curtains in tandem in the manner shown in detail in the drawings. One curtain roller is secured to the stationary part of the door, as shown at the right hand side of Figure 1, while the next roller is fixed to a vertical bar at a proper point in the gate. Of course the roller may be mounted upon any fixed structure at the stationary end of the door or gate, as, for instance the wall of an elevator cage.

The free edge of the right hand curtain 14 is preferably carried around at flat connecting bar 35, secured parallel with the supporting bar 28 of the next roller, and then stitched as at 36. Any mode of attachment suited to the nature of the particular guard or curtain

used is within the invention. It will also be understood that the principle of multiple curtains exemplified in the drawings by showing only two, can be extended for any number.

5 In some cases it may be found desirable to provide means for holding the flexible guard or curtain against the gate at a point or points between the edge of the curtain and the roller. For this purpose I prefer to use 10 a bar 37 extending across the guard and fastened at top and bottom above and below the guard, to one of the vertical bars of which the gate is made.

15 A variety of changes may be made in the structure and arrangement herein shown without departing from the scope of my invention, which is not limited to the details herein shown and described.

20 What I claim is—

1. A single collapsible gate in combination with a plurality of spring-actuated rollers mounted in tandem relation thereon, and a guard curtain mounted on each roller having 25 its free end fixed to the gate, said guard curtains extending in tandem arrangement horizontally across said gate and rolling on and off of said rollers to shorten and lengthen with the collapsing and extension of the collapsible gate.

30 2. A single collapsible gate in combination with a plurality of spring-actuated rollers mounted in tandem relation thereon, and a guard curtain mounted on each roller having 35 its free end fixed to the gate, said guard curtains extending in tandem arrangement horizontally across said gate and rolling on and off of said rollers to shorten and lengthen with the collapsing and extension of the collapsible gate, one of said curtain rollers being 40 mounted at the stationary end of said gate, and a second spring roller mounted directly upon an intermediate portion of the gate, the edge of the curtain on the first named roller being fixed adjacent to said second named roller, which is mounted on an 45 intermediate portion of the gate.

50 3. An automatic guard for a collapsible gate of the character described, comprising a flexible curtain extending horizontally crosswise of the gate, automatic stretching means therefor, and a retaining bar for the curtain fixed to and moving with the gate and adapted to preserve a uniform relative distance from the ends of the curtain when the 55 gate is opened and closed, said curtain being slidable within said retaining bar.

60 4. A single collapsible gate adapted and arranged to extend over a relatively wide opening, in combination with guard curtains mounted thereon in tandem fashion and extending across the gate, a plurality of spring rollers on which said curtains wind and unwind in opening and closing said gate, one 65 at least of said plurality of rollers being

mounted on said gate and having its curtain also fixed at its free end to said gate, said rollers each having a spring adapted to maintain said curtains taut during winding and unwinding, said springs opposing less resistance to the force required for opening said gate than a single spring for maintaining taut a curtain of a length equaling the combined length of the tandem curtains.

70 5. The combination of a collapsible gate and an automatic guard therefor of the character described, comprising a curtain mounting attached to an intermediate part of said collapsible gate, flexible curtains extending in tandem arrangement horizontally crosswise of the gate, automatic stretching means for said curtains, one of said automatic stretching means being on said mounting, and means on said mounting for attaching the end of an adjacent curtain.

75 6. The combination of a collapsible gate and an automatic guard therefor of the character described, comprising a curtain mounting attached to an intermediate part of said collapsible gate, flexible curtains extending 80 in tandem arrangement horizontally crosswise of the gate, automatic stretching means for said curtains, one of said automatic stretching means being on said mounting, and a rod running lengthwise of and attached to said mounting, for attaching the end of an adjacent curtain.

85 7. The combination of a collapsible gate and an automatic guard therefor of the character described, comprising a curtain mounting attached to an intermediate part of said collapsible gate, flexible curtains extending 90 in tandem arrangement horizontally crosswise of the gate, automatic stretching means for said curtain, one of said automatic stretching means being on said mounting, and means on said mounting for attaching the end of an adjacent curtain, said automatic stretching means comprising a spring roller in said 95 mounting, and a guard partially surrounding 100 said spring roller.

105 8. An automatic guard for a collapsible gate of the character described, comprising a flexible curtain extending horizontally crosswise of the gate, automatic stretching means therefor, a guard partially surrounding said automatic stretching means, and a retaining bar for the curtain fixed to and moving with the gate and adapted to preserve a uniform relative distance from the ends of the curtain when the gate is opened and closed, said curtain being slidable within said retaining bar.

110 9. In combination with the collapsible gate of an elevator car, of an interior flexible guard curtain secured to the free end of the gate at one end, and including a spring roller upon which said guard curtain is wound, bearings for said roller, a guard for the roller, and means for securing said guard in a posi- 115 120 125 130

tion protecting said roller and curtain wound thereon.

10. In combination with a collapsible gate, of a flexible protecting device therefor spaced from the top and bottom of said gate, including a spring roller upon which said protecting device is wound, bearings for the roller, and a guard for the roller, adapted to be held in a position protecting said roller and curtain wound thereon.

11. In combination with a collapsible gate, of a guard curtain therefor, including a spring roller upon which said curtain is wound, bearings for the roller, a support to which said bearings are secured, a guard for the roller supported in position to protect said roller and curtain wound thereon, a reinforcing curved bracket for the guard, and means for securing it to the support.

20. 12. In combination with the collapsible gate of an elevator car, an interior guard curtain having one end secured to the free end of the gate, a support, plates secured to the ends of the support and provided with bearings, a spring roller mounted in said bearings upon which the curtain is adapted to be wound, a semi-cylindrical guard for the roller, and means for securing said guard to said plates.

30. In testimony whereof I have hereto affixed my signature.

HAROLD W. SHONNARD.
